2,078,327

DITCHER

James Kinghorn, Youngstown, N. Y.

Application November 20, 1936, Serial No. 111,929

3 Claims. (Cl. 37—98)

The present invention relates to new and useful improvements in ditchers of the type including a substantially V-shaped plow and has for one of its important objects to provide, in a manner as hereinafter set forth, a machine of this character embodying a novel construction and arrangement through the medium of which the plow will operate at a substantially uniform depth at all times.

Another very important object of the invention is to provide a ditching machine of the character described embodying novel means for elevating or lowering the plow for varying the width and depth of the ditch as desired.

Other objects of the invention are to provide a ditcher of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a ditcher constructed in accordance with the present invention.

Figure 2 is a view partially in side elevation and partially in vertical longitudinal sections through the invention.

Figure 3 is a detail view in cross section through one of the mold boards taken substantially on the line 3—3 of Fig. 1.

Figure 4 is a sectional view through the crank axle, showing one of the braces connected thereto.

Referring now to the drawings in detail, it will be seen that the embodiment of the invention which has been illustrated comprises a crank axle 1 having journalled on its end portions supporting wheels 2. The crank axle 1 is journalled on the rear end portion of a tongue 3. Braces 4 extend between the crank axle 1 and the tongue 3 and extending transversely between said braces 4 is a cross member 5. A hand lever 6 is fixed on the crank axle 1 for raising and lowering the rear end of the machine, said hand lever being provided with a suitable latch 7 engageable with a toothed segment 8 on the tongue 3 for releasably securing said lever in adjusted position.

The reference numeral 9 designates generally a substantially V-shaped plow which is mounted beneath the tongue 3, said plow including rear-

wardly diverging mold boards 10 on the forward ends of which a removable point 11 is provided. As illustrated to advantage in Fig. 3 of the drawings, the mold boards 10 include inturned and out-turned upper and lower flanges 12 and 13, respectively.

The plow 9 is mounted on the crank axle 1 through the medium of a frame structure which is designated generally by the reference numeral 14. The frame 14 includes crossed longitudinal and transverse members 15 and 16, respectively, the former being journalled on the crank axle 1. The members 15 and 16 are rigidly secured, at one end, to the flanges 12 of the mold boards 10. Extending between the rear end portions of the longitudinal frame members 15 is a platform 17 for an operator. It will be observed that the construction and arrangement is such that the wheels 2 of the machine are located within the substantially V-shaped plow 9.

Rising from an intermediate portion of the tongue 3 is a post 18 on which a longitudinally extending hand lever 19 is pivotally mounted at an intermediate point. The hand lever 19 is provided with a suitable latch 20 which is engageable with a toothed segment 21 on the post 18 for releasably securing said hand lever in adjusted position. Hand lever 19 is adjustably connected at one end, as at 22, to the upper end of a hanger 23 which rises from the forward end of the plow 9, said hanger 23 passing through a slot 24 which is provided therefor in the tongue 3. A wear plate 25 is provided on the tongue 3 for the hanger 23.

Secured to the lower portion of the hanger 23 and extending through an opening 26 which is provided therefor in the front of the plow 9 is a rod 27. Mounted on the rod 27 is a clevis 28. Depending from the forward end of the tongue 3 is a bracket 29 to the lower end of which a clevis 30 is loosely connected through the medium of a ring 31. The clevis 30 is adapted for connection with the draw bar of a tractor or other suitable draft implement. A rod 32 extends between the clevises 28 and 30.

It is thought that the operation of the device will be readily apparent from a consideration of the foregoing. As the machine is drawn over the ground the comparatively low forward end portion of the inclined plow 9 travels in the ground at a substantially uniform depth under various conditions due to the fact that supporting wheels are provided at the rear end only. It will be noted that the levers 6 and 19 are adapted to be conveniently operated from the platform 17. By rais-

ing or lowering the rear end of the machine through the medium of the lever 6, the width of the ditch may be varied as desired. When the hand lever 6 is actuated the rear portion of the 5 plow 9 is raised or lowered. The forward end of the plow 9 may be raised or lowered to vary the depth of the ditch through the medium of the hand lever 19. The construction and arrangement of the elements 27 to 32, inclusive, is such 10 that the draft is transmitted directly to the plow 9 from the tractor or other source of power.

It is believed that the many advantages of a ditcher constructed in accordance with the present invention will be readily understood, and although 15 a preferred embodiment of the machine is as illustrated and described, it is to be understood that changes in the details of construction and in the combination and arrangement of parts may be resorted to which will fall within the scope of 20 the invention as claimed.

What is claimed is:

1. A ditcher comprising a crank axle, supporting wheels journalled on said crank axle, a substantially V-shaped plow including rearwardly 25 diverging mold boards, said mold boards comprising inwardly extending upper flanges and outwardly extending lower flanges, a frame structure for mounting the plow on the crank axle, said frame structure comprising crossed longitudinal 30 and transverse members rigidly secured, at one end, to the upper flanges of the mold boards, the longitudinal members being journalled on the crank axle, a platform extending transversely between the rear end portions of said longitudinal 35 members, and a lever fixed on the crank axle and operable from the platform for actuating said

crank axle for raising and lowering the rear end of the plow.

2. A ditcher comprising a tongue, a crank axle journalled on the rear end portion of said tongue, supporting wheels journalled on said crank axle, 5 a substantially V-shaped plow journalled on the crank axle, means on the tongue for raising and lowering the forward end of the plow, and means for connecting the forward end of the plow directly to a source of power, the last named means 10 including a rod connected to the plow, a clevis connected to said rod, a bracket depending from the forward end of the tongue, a clevis loosely mounted on the bracket, and a rod connecting the first and second named clevises. 15

3. A ditcher of the class described comprising a tongue, an axle journalled on said tongue, supporting wheels journalled on the axle, a substantially V-shaped plow mounted for swinging adjustment at its rear end portion on the axle, said 20 plow including rearwardly diverging mold boards and a removable point on the forward end portions thereof, said point having an opening therein, a hand lever mounted on the tongue, a hanger connecting the forward end portion of the plow 25 to said hand lever for raising and lowering said plow, a rod connected to the hanger and extending through the opening in the plow point, a clevis loosely connected to said rod, another rod loosely 30 connected to the clevis, a clevis loosely mounted on the forward end portion of the second named rod for connection with a draft implement, and a bracket supporting the second named clevis on the tongue. 35

JAMES KINGHORN.
